UNITED STATES PATENT OFFICE.

GEORGE A. GLENDENING, OF BOWLBY, WEST VIRGINIA.

DESIGN FOR A BURIAL-VAULT.

44,636.

Specification for Design.

Patented Sept. 9, 1913.

Application filed March 22, 1913. Serial No. 756,225. Term of patent 14 years.

To all whom it may concern:

Be it known that I, GEORGE A. GLENDENING, a citizen of the United States, residing at Bowlby, in the county of Monongalia and State of West Virginia, have invented a new, original, and ornamental Design for Burial-Vaults, of which the following is a specification, reference being had to the accompanying drawing, forming part thereof.

Figure 1 is a front elevation of a burial

vault showing my new design. Fig. 2 is a side elevation thereof.

I claim:

The ornamental design for a burial vault, as shown.

GEORGE A. GLENDENING.

Witnesses:

L. D. BOYLES,

W. B. HALBERT.
